MANUEL AURELIO SERRA Y PÉREZ, OF HABANA, CUBA

TACKLE TO SUPPORT SCAFFOLDS OR SIMILAR DEVICES

Application filed September 10, 1926, Serial No. 134,740, and in Cuba June 22, 1926. Renewed October 3, 1929.

- This invention refers to scaffold supports or similar devices, and has for its main object, to provide a device of this kind, which when used in working on a building, permits 5 the workman himself who is standing on the scaffold to control, at will, the greater or lesser heights of same regarding the ground, by a slight effort, and without the least danger of accident to himself or fellow workmen. 10 One advantage of this invention, is that the device may be suited to long lines of scaffolding, which makes it specially useful in the largest building works. Other objects and advantages will be found in the course of 15 these specifications, with the aid of the figures in the attached drawings, specially by those persons who are experts in the art to which this invention pertains.

In the drawings:

- 20 Fig. 1, is a fragmentary, front elevation, showing sectioned parts of the invention,

Fig. 2, is a vertical section according to lines 2—2 of Fig. 1.

In usual cases, as shown in the drawing, 25 the platform 1 of the scaffold is sustained by a hanging bracket formed by a U shaped frame 2 on which rests the platform 1, and through the ends of the branches of the frame is gyratorially mounted a horizontal shaft 3, 30 which serves to bear a hanging bracket 4 which has two standards for each end 5 and 5', fastened to the shaft 3, and having secured between said standards 5 and 5' the drums 6 and 7 for the coiling of the cables 8 and 9 on which the supports are suspended. 35

The elevating mechanism comprises a worm wheel 10 which is fastened to the shaft 3 and which meshes with a screw 11 mounted between standards 12 integral with the bracket 4.

The shaft of the screw 11 projects outwardly from one of the standards 12, and secured to same is the sprocket wheel 13 for the chain 14 which operates the raising or lowering of 45 the scaffold.

The ends of said shafts end in universal joints 15 for coupling by means of a horizontal shaft 16 ending also in like joints 16'.

As explained, it will be understood that a workman on the platform 1 of the scaffold, 50 can regulate the greater or lesser heights of same regarding the ground, by operating the chain 14, thereby transmitting the movement to the shaft 3 by the gear 10 and worm 11 and wind or unwind the ropes 8 and 9, on 55 the drums 6 and 7, by which the bracket 2 and the scaffold 1 are raised or lowered, accordingly.

It is obvious that within the principles of construction before explained, many modifications may be made without departing from the essential idea of the invention, which is as claimed in the following claims:

Claims:

1. A cable-suspended scaffold support including a shaft, a pair of cable drums fixed thereon, a yoke hung from the shaft and adapted to cradle one end of a scaffold, a second yoke hung from the shaft and held against endwise movement thereon by the 70 first yoke, said second yoke including arms preventing endwise movement of the cable drums on the shaft, a gear on the drum shaft, an operating shaft supported on the second yoke and carrying a worm engaged with the 75 gear, and means for rotating the operating shaft.

2. A cable suspended scaffold support comprising a pair of U-shaped frames, a shaft mounted in each frame, a worm wheel on each 80 shaft, a pair of drums on each shaft upon which the supporting cables are mounted, a bracket suspended from each shaft, a worm mounted in each bracket and meshing with the worm wheel, a shaft between the worm shafts 85 and having a universal connection therewith, and means for operating the worms.

3. A cable suspended scaffold support comprising a pair of U-shaped frames, a shaft mounted in the upper ends of the members of 90

each frame, a worm wheel on each shaft, a pair of drums on each shaft, supporting cables on the drums, a bracket suspended from each shaft, each bracket having pairs of arms, between each pair of which a drum is disposed, 5 a worm wheel mounted in each bracket, a shaft between the shafts of the worm wheels and having universal connection therewith, a chain wheel on one worm shaft, and a chain 10 on said wheel for operating it.

In testimony whereof I have signed my name to this specification.

DR. M. AURELIO SERRA y PÉREZ.
